CLAIM

The ornamental design for a jar, as shown and described.

DESCRIPTION

FIG. 1 is an isometric view of a top, front, and interior of a first embodiment of a jar;

FIG. 2 is a front elevational view of the jar of FIG. 1;

FIG. 3 is a rear elevational view of the jar of FIG. 1;

FIG. 4 is a right side elevational view of the jar of FIG. 1;

FIG. 5 is a left side elevational view of the jar of FIG. 1;

FIG. 6 is a top plan view of the jar of FIG. 1;

FIG. 7 is an isometric view of a top, front, and interior of a second embodiment of a jar;

FIG. 8 is a front elevational view of the jar of FIG. 7;

FIG. 9 is a rear elevational view of the jar of FIG. 7;

FIG. 10 is a right side elevational view of the jar of FIG. 7;

and,

FIG. 12 is a top plan view of the jar of FIG. 7.

The dash-dash-dash broken lines are included for the purpose of illustrating portions of the jar that form no part of the claimed design. The dash-dot-dash broken lines depict the boundaries of the claim and form no part thereof.

1 Claim, 8 Drawing Sheets
